SUPPORT FOR CONCRETE REINFORCEMENTS

Filed Aug. 5, 1927

Fig. 2

Inventor
W.E. Mathews

By *W.E. Mathews* Attorney

UNITED STATES PATENT OFFICE.

WILLIAM E. MATHEWS, OF BIRMINGHAM, ALABAMA.

SUPPORT FOR CONCRETE REINFORCEMENTS.

Application filed August 5, 1927. Serial No. 210,834.

My invention relates to a support for concrete reenforcing steel and is more particularly directed towards the designing of a new and improved type of support for the temperature or carrying bars on which the raised ends of the arch bars rest.

The object of my invention is to provide a support which is very simple and inexpensive in its structure, which can be shipped knocked down; which is readily adjustable to support the carrying bars and arch bars at any desired height within a reasonable range from the base of the slab or support for the concrete to be reenforced; and which 10 possesses the distinct advantage of positively gripping the carrying bars so as to support the reenforcement without requiring any tacking to the floor, tying, or showing through.

More particularly, my invention contemplates the provision of a support formed of a pair of straight notched rods connected loosely by a yoke which is preferably formed as a curved plate with spaced holes in its 20 ends to receive the rods. It is contemplated that the carrying bars will be received between the support rods while resting upon the yoke, thereby permitting said bars, as they spread apart at their base into operating position, to clamp and bind upon the carrying bars and thus interlock the support firmly therewith. By providing a plurality of notches, the rods will permit a reasonable adjustment in height of the supporting yokes 25 for the carrying bars and thus adapt the same support to serve under a reasonably wide range of operating conditions.

My invention further comprises the novel details of construction and arrangement of parts, which, in its preferred embodiment is 30 hereinafter more particularly described and claimed, and which is illustrated in the accompanying drawings which form a part of this specification.

In the drawings:

Fig. 1 is a view showing the support in position under a temperature bar upon which the arched reenforcing steel rests.

Fig. 2 is an enlarged end view of Fig. 1.

Fig. 3 is a detail view of the yoke.

Similar reference numerals refer to similar parts throughout the drawings.

The embodiment of my invention is shown adapted to form a high support for a temperature or carrying bar 4 which is disposed transversely to and serves to carry the high ends 5 of the arch bars 6 forming the reinforcement steel for a concrete slab of the mushroom heads of columns. Each support comprises a pair of inclined legs 7 preferably formed of steel rods having sufficient diameter for the duty contemplated and each provided near one end with a series of equidistantly spaced transverse notches 8. These rods 7 have their upper ends inserted through the holes 9 in a yoke plate 10 preferably formed with a slight middle bend adapted to receive center and support a carrying bar 4 which, by engagement with the upper ends of the rods, serves to hold them interlocked with the outer ends of the yoke by engagement in their notches 8. The rods 7, as they are spread apart to set up the support will fulcrum upon the outer ends of the yoke and clamp the carrying bar with a grip which increases with the head on the support. The bend in the yoke 10 enables it to readily set itself and take its load without distortion or subsequent settlement and the whole support is thus very positively and rigidly interlocked with the carrying bar it supports. It is obvious that the yoke can be adjusted to sufficient heights by interlocking it with the desired notches 8 on the support rods 7. These supports are usually spaced on five to six 50 foot centers along each carrying bar 4, and they are readily collapsible, easily set up on the job, and being adjustable to different heights will require but a minimum of stocking of material to provide the needed high supports.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what

I claim as new and desire to secure by Letters Patent, is:—

1. A high support for reenforcing steel, comprising a pair of rods, a cross connection to which the rods are pivoted, said cross connection being adjustable on the rods and adapted to support between them a concrete reenforcing member.
2. A high support for concrete reenforcement, comprising a pair of rods having a plurality of notches near one end, a yoke plate perforated to permit the rods to be inserted therethrough and engaged in opposed notches in the rods, and a reenforcement bar adapted to rest on said yoke between the upper ends of the rods.
3. A high support for concrete reenforcement, comprising a pair of notched rods, and a yoke having spaced holes adapted to receive the rods, the yoke being adapted to engage in the rod notches and to support a reenforcing bar and its holes being spaced to cause the rods as they tend to spread apart under their load to clamp the reenforcing bar above the yoke.
4. A high support for concrete reenforcement, comprising a pair of notched rods, and a bar supporting yoke having holes adapted to snugly receive the rods, the holes being spaced a lesser distance than the width of the reenforcing bar to be supported by the yoke, whereby the upper ends of the rods when disposed in inclined operating position are adapted to be held by said reenforcing bar in interlocked relation with notches on said rods.
5. A high support for concrete reenforcement, comprising a pair of rods, and means adjustable vertically on the rods and adapted to connect them for relative angular play in a vertical plane, said means being adapted to support a reenforcing bar in position to be clamped between the rods and by its load and size to interlock the connecting means in adjusted position on the rods.

In testimony whereof I affix my signature.
WILLIAM E. MATHEWS.
